UNITED STATES PATENT OFFICE.

CHARLES C. BLAKE, OF BROOKLINE, MASSACHUSETTS, ASSIGNOR TO C. C. BLAKE, INCORPORATED, OF BOSTON, MASSACHUSETTS, A CORPORATION OF NEW YORK.

METHOD OF MAKING SHOES.

1,284,863.

Specification of Letters Patent. Patented Nov. 12, 1918.

Original application filed August 16, 1913, Serial No. 785,142. Divided and this application filed October 20, 1915. Serial No. 58,978.

To all whom it may concern:

Be it known that I, CHARLES C. BLAKE, a citizen of the United States, residing at Brookline, in the county of Norfolk and 5 State of Massachusetts, have invented a new and useful Improvement in Methods of Making Shoes, of which the following is a specification.

The present invention relates to methods 10 of connecting members together such, for instance, as the shoe upper, welt and insole of a welt shoe.

Such insoles are usually prepared for the sewing operation, that is, the operation of 15 securing the shoe upper, welt and insole together, from a sole-shaped blank by splitting it along its edge around the shank and forepart to form a lip and a feather or by splitting its edge and also cutting one face 20 of the blank within the edge cut thereby forming a flap parallel to the lip. The lip or lip and flap are turned up at right angles to the cut face of the blank to form a marginal abutment the base of which receives the 25 stitches during the sewing operation. After the sewing and inseam trimming operations the cavity bounded by the marginal abutment hereinbefore referred to is filled with ground cork mixed with a suitable binder. This 30 construction permits the shoes to be exhibited to the trade with the forepart of the insoles in a flat condition. As soon, however, as these shoes are worn the cork filler becomes displaced in the space between the 35 inner and outer soles resulting in the formation of a concave trough in the forepart of the insole. The formation of a trough in the forepart of the insole is a source of great discomfort and injury to the feet.

40 I propose to prevent the formation of this objectionable trough in the forepart of the insole by eliminating the necessity for the formation of a marginal abutment to receive the inseam stitches and consequently the 45 need of using a filler between the inner and outer soles to fill the cavity bounded by the marginal abutment. As a substitute for the marginal abutment to hold the inseam stitches I employ tongues formed in one face 50 of the insole over which the thread connecting the welt, upper and insole of a welt shoe

or the sole and upper of a turn shoe is looped. It has been proposed heretofore to employ tongues to hold the stitches in both welt and turn shoes, but the construction of 55 the tongues and the methods employed for their formation have been found impracticable.

The method employed in forming the tongues for holding the stitches in turn shoes 60 consisted in providing a sewing machine with a V-shaped chisel which cuts a V-shaped incision in the face of the sole thus forming a tapering V-shaped tongue integral therewith over which the thread connecting the 65 upper and sole looped. This method was found impracticable, however, as it proved to be impossible for the operative to hold the shoe in his hand and swing and tip the shoe at the proper time and to the proper extent 70 so that the chisel would uniformly penetrate the sole at the correct angle and depth. It was found that any deviation in the angle or depth of cut seriously affected the size or position of the tongues which prevented the 75 sewing instrumentalities from properly handling the thread and setting it in position over the tongues. As these tongues also taper in width and thickness throughout their length it was found impossible to properly 80 set the thread in position thereover, even when correctly formed, as the tension with which the stitch was set caused the tapered tongue to buckle and thus permit the thread to slip therefrom.

85 For welt work it was proposed to first channel the insole and then slit the channel flap transversely into short sections, the alternate ones of which were used as tongues. While by this method tongues were formed 90 having a uniform width throughout their length this method also proved to be impracticable as it involved a separate channeling operation and it produced tongues tapering in thickness which in the same manner as 95 the V-shaped tongues permitted the tongue to buckle under the tension employed in setting the stitch and the thread to slip therefrom.

100 The object of the present invention is to provide a method of forming the tongues in one of the members of the parts to be

connected whereby the stitches may be held in a reliable and satisfactory manner.

To the accomplishment of this object and such others as may hereinafter appear the 5 features of the invention relate to certain methods of manufacture hereinafter described and then set forth broadly and in detail in the appended claims which possess advantages readily apparent to those skilled 10 in the art.

While the invention may be utilized to connect various components of an article together, I have selected an insole and the manner of its connection with the shoe upper 15 and welt of a welt shoe for the purpose of illustration as it shows the invention in its best form at present devised.

The various features of the present invention will be readily understood from an 20 inspection of the accompanying drawings, in which,

Figure 1 is a plan of an insole provided with a series of furcular slashes along the peripheral margin of one face;

25 Fig. 2 is a detail elevation, partly in section, showing the manner in which the furcular slashes are formed in the insole;

Fig. 3 is a perspective of the gouge employed to slash the insole;

30 Fig. 4 is a detail plan showing the awl penetrating the edge of the insole, intersecting the slash below the surface of the insole, and separating the tongue bounded by the tines of the fork, the face of the insole 35 and the awl cut, from the body portion of the insole;

Fig. 5 is a detail sectional elevation of the parts illustrated in Fig. 4;

Fig. 6 is a sectional elevation similar to 40 Fig. 5 showing the awl withdrawn;

Fig. 7 is a detail plan showing the passing of the thread through the welt, upper and insole by means of a needle;

Fig. 8 is a perspective, partly in section, 45 showing the operation of the needle which enters the work in the split of the welt and emerges from the face of the sole through the stem of the furcular slash;

Figs. 9, 10 and 11 are elevations, partly 50 in section, showing various positions of the looper in looping the thread over the tongue and subjecting the tongue to pressure; and

Fig. 12 is a perspective, partly in section, 55 of the finished shoe embodying the features of the present invention.

In the illustrated embodiment of the invention an insole 1 is provided with a series of furcular slashes 2 which are formed normal to one face of the insole along the 60 peripheral margin thereof. These furcular slashes may have any forked construction either with or without a stem, as may be found desirable or expedient. That is, they may take the form shown at A, or B, or C, (Fig. 1). It is preferred, however, to em-

ploy a slash of the type shown at C which comprises a fork 3, having two tines 4, and a stem 5 connected to the fork. The insole is also provided with a series of awl cuts 6, (Fig. 6) each one of which extends parallel 70 to the slashed face of the insole from the edge of the insole to one of the slashes which it intersects below the surface of the insole thus separating the material of the insole bounded by the tines 4 of the fork 75 from the body portion of the insole and forming a tongue 7, (Figs. 5, 6 and 7) integral therewith. As the furcular slashes and awl cuts are formed normal to the face and edge of the insole respectively the sides 80 of the tongues are perpendicular to the face of the insole and the top and bottom faces of the tongues are parallel. This construction produces a tongue substantially uniform in width and thickness throughout its 85 length thus insuring a substantial piece of stock to hold the stitches. With this construction all danger of the tongue buckling so that it can be pulled back into the awl cut when the stitch is being set thus permitting the thread to slip from the tongue 90 is obviated.

With the insole thus prepared it may be connected to a shoe upper and welt in any suitable manner found desirable or expedient. 95 Preferably a shoe upper 8 is first lasted to the edge face of the insole and then the welt or a reinforcing strip is assembled with the lasted shoe. The upper is thus interposed between the insole and welt 100 with its edge substantially flush with the tread or bottom faces of the insole and welt. Furthermore, the contacting faces of the welt and upper and of the upper and insole are arranged in parallel planes normal to 105 the exposed face of the insole. The upper, insole and welt are connected together by a thread 10 which extends progressively along a longitudinal slit 11, 110 formed in the welt 9, through the welt, upper and insole, over the tongue 7, and back through the insole, upper and welt to the slit therein. As shown in Fig. 6 the slit 11 in the welt is formed in the same plane as 115 the bottoms of the tongues in the insole.

While in its broader aspects the invention 120 contemplates preparing the insole with tongues prior to the sewing operation, it is preferred to form the tongues in the machine which connects the shoe upper, welt and insole together. To this end the machine is provided with a gouge 12, (Figs. 2 and 3) arranged to reciprocate at right angles to the face of the insole and provided with two cutting edges one of which, the edge 13, forms the stem of the furcular 125 slash and the other one of which, the edge 14, forms the fork and its two tines. In order to limit the depth of the slash the gouge carries a block 15 which strikes 130

against the surface of the insole during the downward movement of the gouge, (Fig. 2). After the gouge 12 forms the slash it is withdrawn and the awl 16 is actuated in the 5 plane of the slit 11 through the welt, upper and insole, (Figs. 4 and 5). The awl cut intersects the slash below the surface of the insole and penetrates the insole beyond the juncture of the stem and fork thus forming 10 a tongue from the material bounded by the tines of the fork. As the block 15 limits the downward movement of the gouge in the same manner for each succeeding slash, and as the gouge and awl operate normal to the 15 face and edge of the insole, respectively, it will be apparent that the tongues are uniformly formed, a result heretofore considered impossible.

As soon as the awl withdraws, a straight 20 eye-pointed needle 17 carrying the thread passes through the awl cut formed in the welt, upper and insole finally emerging through the stem of the slash above the surface of the insole, (Figs. 7 and 8). After 25 the needle has passed completely through the work in the manner illustrated in Fig. 8 it is withdrawn from the work and forms a loop in the thread. During the first part 30 of the return stroke of the needle the loop is engaged by a nose 18 formed upon an oscillating looper 19. The looper first oscillates in the direction of movement of the retreating needle to throw the loop over one of the tongues, (Fig. 9). Just before 35 the thread is looped over the tongue the looper is dropped upon the tongue, (Fig. 10), and when the needle withdraws from beneath the tongue, the looper is oscillated in the reverse direction which causes the 40 looper to release the thread and to wipe over the tongue and depress it substantially flush with the surface of the sole, (Fig. 11), after which the looper is returned to its original position. The stitch is now set by 45 drawing the thread taut over the tongue.

Those skilled in the art will readily appreciate from an inspection of Fig. 12 the important advance in the art of shoe making initiated by the present invention. A 50 shoe embodying the features of the present invention is more comfortable to wear than welt shoes heretofore devised as the construction thereof eliminates the possibility for the formation of the objectionable 55 trough in the forepart of the insole. It is also more economical to manufacture as a large number of the operations heretofore considered essential in the formation of welt shoes are eliminated particularly those operations 60 formerly employed to prepare the insole for the sewing operation and to fill the cavity between the inner and outer soles. It will be readily apparent to those skilled 65 in the art that the shoe of the drawings is more flexible than the shoes made by

the Goodyear process since the stiff rib for holding the stitches is eliminated. This flexibility is further increased by the stems of the furcular slashes formed in the insole. For many reasons obvious to those 70 skilled in the art the shoe illustrated in Fig. 12 is more durable than the welt shoes heretofore devised. One reason for this is that the inseam stitches of the improved shoe are substantially arranged in the plane 75 of flexure of the shoe while in the former welt shoe the inseam stitches were not so arranged and consequently were subjected to strain every time the shoe flexed in walking.

While the illustrated embodiment of the present invention is directed to an improved method of connecting the upper, welt and insole of a welt shoe it is not to be understood as limiting the scope of the claims 80 where the context otherwise permits to the exclusive practice of this method in the manufacture of welt shoes as it will be apparent to those skilled in this and other arts that the methods herein disclosed may be 85 advantageously employed in connecting parts of many articles.

The operations which are performed as above described and illustrated are those which are preferred in practising the present invention. It is to be understood, however, that except as defined in the claims 90 the invention is not limited to the precise methods illustrated and described and that the steps of the method may be varied or 95 modified without departing from the spirit of the invention.

It will also be apparent to those skilled in the art that the present invention is useful in the manufacture of other kinds of shoes 100 than welt shoes, therefore, the term "sole" used in the following claims must be construed to mean any kind of a sole whether an insole or an outsole.

What is claimed as new, is:—

1. That improvement in the art of fastening two members to each other which consists in forming in one member a series of furcular slashes; forming in both members a series of cuts at right angles to the 115 slashes each cut intersecting a slash below the surface of the slashed member and freeing the tongue bounded by the tines of the slash, the face of the slashed member and the cut from the body portion of the slashed 120 member; and passing a thread through the members and over the tongues, substantially as described.

2. That improvement in the art of securing a shoe upper, its insole and welt together, which consists in forming along the peripheral margin of one face of the insole a series of furcular slashes; forming a series of cuts parallel to the face of the insole through the welt, upper and insole each cut 130

intersecting a slash below the surface of the insole and freeing the tongue bounded by the tines of the slash, the face of the insole, and the cut in the insole from the 5 body portion of the insole; and passing a thread through the welt, upper and insole and over the tongues, substantially as described.

3. That improvement in the art of securing 10 a shoe upper, its insole and welt together, which consists in gouging the peripheral margin of one face of the insole; awling through the welt, upper and edge of the insole to form a cut intersecting the gouge- 15 slash below the surface of the insole and free the tongue formed by the gouge from the body portion of the insole; and passing a thread through the awl hole in the welt, upper and insole and over the tongue, substan- 20 tially as described.

4. That improvement in the art of securing 25 a shoe upper, its insole and welt together, which consists in cutting a series of furcular slashes in the peripheral margin of one face of the insole, the depth of said slashes being limited by a depth gage; awling through the welt, upper and insole to intersect the furcular slashes below the surface of the insole and free the tongues 30 formed by the tines of the slashes from the body portion of the insole; passing a thread through the awl holes; and looping the thread over the tongues, substantially as described.

5. That improvement in the art of preparing 35 soles for the inseaming operation which consists in slashing the face of the sole, and intersecting the slash in the sole below the surface thereof by a second cut 40 normal to the first cut, substantially as described.

6. That improvement in the art of preparing 45 soles for the inseaming operation which consists in cutting a series of furcular slashes in the face of the sole and separating the material bounded by the tines of the slashes from the body portion of the sole by a series of cuts below the surface of the sole and normal to the edge thereof, 50 substantially as described.

7. That improvement in the art of making 55 shoes which consists in assembling an insole, an upper and a welt with the bottom faces of the welt and insole and free edge of the upper substantially flush; forming tongues in the bottom face of the insole; passing a thread through the welt, upper and insole; and looping the thread over the tongues, substantially as described.

8. That improvement in the art of preparing 60 soles for the inseaming operation which consists in forming in a step by step manner a series of pairs of intersecting slashes near the margin of the sole, the 65 slashes forming a pair being arranged nor-

mal to the face and edge of the sole respectively, substantially as described.

9. That improvement in the art of making 70 welt shoes which consists in slitting a welt longitudinally along one edge; assembling the welt with a lasted shoe comprising an insole and an upper secured to the edge face thereof; forming tongues in the bottom face of the insole; passing a thread through the welt, upper and insole; and 75 looping the thread over the tongues, substantially as described.

10. That improvement in the art of preparing 80 soles for the inseaming operation which consists in forming a series of stitch-anchoring tongues uniform in width and thickness substantially throughout their length along the margin of one face of the sole, substantially as described.

11. That improvement in the art of making 85 welt shoes which consists in slitting a welt longitudinally along one edge; assembling the welt with a lasted shoe comprising an insole and an upper secured to the edge face thereof; and passing a thread 90 along the slit in the welt and through the welt, upper and insole.

12. That improvement in the art of making 95 welt shoes which consists in slitting a welt along one edge; assembling the welt with a lasted shoe comprising an insole and an upper secured to the edge face thereof and with the unslit edge of the welt, the opposite faces of the marginal portion of the upper and edge face of the insole in 100 parallel planes normal to the face of the insole, and passing a thread along the slit in the welt and through the welt, upper and insole.

13. That improvement in the art of making 105 welt shoes which consists in assembling a welt with a lasted shoe comprising an insole and an upper secured to the edge face thereof with the contacting faces of the welt and upper and of the upper and insole in 110 parallel planes normal to the face of the insole, and uniting the welt, insole and upper.

14. That improvement in the art of making 115 welt shoes which consists in securing an upper in lasted position to the edge face of an insole, and then securing a welt to the united upper and insole by means other than the means for uniting the upper and insole.

15. That improvement in the art of making 120 welt shoes which consists in securing an upper in lasted position to the edge face of an insole and then securing a welt slit longitudinally along the edge face of the welt which is exposed in the finished shoe by 125 stitches anchored in the base of the slit in the welt and also in the insole.

16. That improvement in the art of making 130 welt shoes which consists in securing an upper in lasted position to the edge face of

an insole, assembling a welt and the lasted shoe with the welt arranged entirely outside the peripheral edge of the insole, and uniting the welt in its assembled position to the 5 lasted shoe.

17. That improvement in the art of making welt shoes which consists in securing an

upper in lasted position to an insole and a welt to the lasted shoe by means that performs its securing function by engagement 10 both with the edge face of the insole and that portion of the upper engaged with the edge face of the insole.

CHARLES C. BLAKE.
